United States Patent Office

Des. 204,677
Patented May 10, 1966

204,677

MOBILE

Alfred Sauer, Box 10, Litchfield, Ohio

Filed Sept. 15, 1964, Ser. No. 81,729

Term of patent 14 years

Cl. D29—1)

Fig. 2.

FIG. 3.

I claim:

The ornamental design for a mobile, substantially as shown.
